Fig. 5.

Fig. 6.

FIG. 1 is a side elevational view of my threaded connector embodying my new design;

FIG. 2 is a view similar to FIG. 1 with the threaded connector rotated 90° to show the central portion in elevation not seen in FIG. 1;

FIG. 3 is a partial top plan view of the central portion of the threaded connector shown in FIG. 2;

FIG. 4 is a partial rear elevational view of the central portion shown in FIG. 2 but with the threaded connector rotated 180°;

FIG. 5 is a left end view of the threaded connector shown in FIG. 1; and

FIG. 6 is a right end view of the threaded connector shown in FIG. 1.

The ends are fragmented for convenience of illustration and indicate indeterminate length, it being understood that the rod is circular in cross section throughout.

I claim:

The ornamental design for the threaded connector, as shown and described.
